United States Patent

Des. 241,684
Patented Sept. 28, 1976

241,684

HAND MIRROR

Arnold Rose, Providence, R.I., assignor to
Trina, Inc.

Filed June 30, 1975, Ser. No. 591,441

Term of patent 14 years

Int. Cl. D28—03

U.S. Cl. D86—10 H

FIG. 1

FIG. 2

FIG. 3

FIG. 1 is a front elevational view of a hand mirror showing my new design, the mirror having the same appearance in front and rear elevation;

FIG. 2 is a side edge view thereof, the mirror having the same appearance from both side edges; and

FIG. 3 is a top plan view thereof, the mirror having the same appearance in both top and bottom plan views.

I claim:

The ornamental design for a hand mirror, substantially as shown and described.
